Primary Examiner — Michael C Stout*Assistant Examiner* — Melvin L Davis(74) *Attorney, Agent, or Firm* — Fish & Richardson P.C.(57) **CLAIM**

The ornamental design for a soft doll, as shown and described.

DESCRIPTION

FIG. 1 is a front view of our soft doll;
 FIG. 2 is a back view thereof;

FIG. 3 is a right side view thereof; and
 FIG. 4 is a left side view thereof.

FIG. 5 is a front view of our soft doll with an opened jacket.
 FIG. 6 is a front view of our soft doll with a closed jacket;

FIG. 7 is a back view thereof;

FIG. 8 is a top view thereof;

FIG. 9 is a bottom view thereof;

FIG. 10 is a right side view thereof; and,

FIG. 11 is a left side view thereof.

The broken lines illustrate portions of the soft doll that form no part of the claimed design.
